UNITED STATES PATENT OFFICE.

PHILIPP MENGES, OF NEW YORK, N. Y.

PIANO-ACTION.

SPECIFICATION forming part of Letters Patent No. 317,660, dated May 12, 1885.

Application filed July 11, 1884. (No model.)

To all whom it may concern:

Be it known that I, PHILIPP MENGES, of the city of New York, in the county and State of New York, have invented a new and Improved Piano-Action, of which the following specification is a full, clear, and exact description.

This invention relates to an improvement in piano-actions, by which the jack will be always placed in the proper position under the hammer-butt when the key is depressed, even though the key were not entirely released during the preceding tone. To this effect I make the jack jointed and provide it with a bevel, which bears against a bevel on the regulating-rail or its equivalent, all as will be hereinafter more fully set out.

In the accompanying drawings, Figure I is a side view of my improved piano-action, showing it for application to a square piano, the key being depressed. Fig. II is a vertical longitudinal section through the same with the key raised. Fig. III is a detail side view of the upper arm of the jointed jack, and Fig. IV a detail side view of a modification of the hammer and butt which is used in upright pianos.

The letter *a* represents the key of a piano. *b* is the bottom piece, to which the jack is pivoted. This jack, which will be hereinafter more fully described, is composed of two arms, *c* *d*, pivoted together. The lower arm, *c*, is connected with the customary jack-spring, *e*.

f is the regulating-rail, also hereinafter more fully described, and *g* is the regulating-screw passing through the rail.

h is the hammer-butt, pivoted to the fixed hammer-flange *i*, and also pivotally connected to the arm *d* of the jack.

j is the hammer, *k* the back-check, and *l* the hammer-rail, all as customary.

The lower arm, *c*, of the jack has the customary projection, *c'*, at its bottom, which strikes the screw *g* when the key is depressed, and thereby throws the upper part of the arm backward—to wit, toward the hammer. Near the upper part the arm *c* is provided with an inclined plane or bevel, *c''*, and the hammer-rail *f*, or an equivalent stop, is provided opposite thereto with a corresponding cushioned bevel, *f'*. I prefer to employ, in place

of one long regulating-rail extending from right to left of the piano, short stops—one for each jack.

The upper arm, *d*, of the jack is provided with upwardly and downwardly extending lugs, Fig. III, so as to straddle both the arm *c* and also the hammer-butt *h*, to each of which it is pivoted by a pin passing through the lugs. At the middle the arm *d* is solid, and opposite this solid portion the arm *c* has an upward cushioned extension, *c'''*, as shown.

The hammer-butt *h*, to receive the pivot-pin of arm *d*, has a slot, *m*, also cushioned. In this slot the pin has a slight play, which allows the hammer to fly up, even after the pin ceases to press the butt up.

The operation of the device is as follows: When the key *a* is depressed, the arms *c* *d* of the jack are in a straight line vertically, and transmit the motion in proper manner to the hammer-butt, causing the hammer to strike the string. As soon as the projection *c'* strikes the screw *g* the arm *c* will be thrown backward—to wit, toward the hammer—carrying the lower end of the arm *d* with it, so that both arms form an obtuse angle between them. The beveled face *c''* will be brought to rest upon the beveled face *f'*, and in this position, which is shown in Fig. I, the parts will remain until the release of the key *a*. On the partial or entire release of the key the beveled face *c''* will glide along the beveled face *f'*, and thereby the arm *c* (aided by spring *e*) will be thrown forward, carrying lower portion of arm *d* with it, until the arms *c* *d* are again in a straight line. During this motion the extension *c'''* will have pressed against the body of arm *d* and thereby aided in throwing said arm forward with arm *c*. Thus the jack being straightened is in proper position under the butt for a new depression of the key.

I prefer to make the stop or rail *f* adjustable toward or away from the jack, so that the amount of throw given by the bevel *f'* to the jack may be regulated. To this effect I slot the hammer-rail *l*, Fig. II, and through this slot insert the screw *n*, which fastens rail or stop *f* to the hammer-rail *l*. By loosening said screw the rail *f* may be moved backward or forward to the proper amount, whereupon the screw *n* is again tightened. At the back the rail

f is grooved longitudinally, to receive a guide-pin, *n'*, which prevents the rail *f* from turning on screw *n*.

In Fig. IV I have shown the hammer and hammer-butt adapted for an upright piano. The parts are all of the customary construction, and the hammer-butt is connected to the jointed jack in the same manner as has been hereinbefore described in relation to square pianos. In order, however, to prevent the pin of the upper arm, *d*, from slipping out of the slot *m*, and also for drawing back the hammer, the mouth of said slot is closed by a hook, *o*, as shown. With this construction I may dispense with the bridle-wire and bridle usually employed.

My action may be used in grand, square, and upright pianos.

I claim as my invention—

1. The combination, in a piano-action, of jointed jack having a beveled edge with a stop having a beveled edge, substantially as herein shown and described.

2. The combination, in a piano-action, of arm *c*, having projection *c'*, beveled edge *c''*, and extension *c'''*, with the stop *f*, having cushioned

beveled edge *f'*, and with arm *d*, substantially as specified.

3. The combination, in a piano-action, of jointed jack *c d* with beveled stop *f*, which is adjustable toward or away from the jack, substantially as specified. 30

4. The combination, in a piano-action, of jointed jack *c d* with hammer-butt *h* and hook *o*, substantially as specified. 35

5. The combination of the following elements: key *a*, bottom piece, *b*, jointed jack *c d*, spring *e*, stop *f*, screw *g*, hammer-butt *h*, hammer-flange *i*, hammer *j*, back-check *k*, and hammer-rail *l*, substantially as specified. 40

6. The combination, in a piano-action, of a hammer-butt, *h*, with a jack composed of the jointed arms *c d*, the lower arm, *e*, having the upwardly-projecting extension *c'''*, which is adapted to bear against the body of the upper arm, *d*, at the release of the key, substantially as specified. 45

PHILIPP MENGES.
